Filed Dec. 9, 1971, Ser. No. 209,590

Term of patent 14 years

Int. Cl. D6—06

U.S. Cl. D54—1 A

FIG. 1 is a perspective view of a ladder attachment for extending and leveling ladders, showing my new design;

FIG. 2 is a side elevational view thereof; the other side, not shown, is the mirror image thereof;

FIG. 3 is a rear elevational view thereof;

FIG. 4 is a front elevational view thereof; and

FIG. 5 is a top plan view thereof, with cup-like bottom member omitted for clarity and ease of illustration.

I claim:

The ornamental design for a ladder attachment for extending and leveling ladders, substantially as shown and described.
